UNITED STATES PATENT OFFICE.

AURIN M. CHASE, OF SYRACUSE, NEW YORK.

INTERNAL-COMBUSTION-ENGINE GOVERNOR.

1,218,981.

Specification of Letters Patent. Patented Mar. 13, 1917.

Application filed May 29, 1913. Serial No. 770,616.

To all whom it may concern:

Be it known that I, AURIN M. CHASE, of Syracuse, in the county of Onondaga and State of New York, have invented a certain 5 new and useful Internal-Combustion-Engine Governor, of which the following is a specification.

This invention has for its object the production of an internal combustion engine 10 governor which is particularly simple in construction and highly efficient in use and it consists in the combinations and constructions hereinafter set forth and claimed.

In describing this invention reference is 15 had to the accompanying drawings in which like characters designate corresponding parts in all of the views.

Figure 1 is a plan view of my governor, the contiguous portion of the intake pipe 20 and the cylinders of the internal combustion engine being also shown.

Fig. 2 is a horizontal cross-sectional view of this governor.

Fig. 3 is an elevation looking upwardly 25 in Fig. 2, the cap, holding the valve in position, being removed.

Fig. 4 is a perspective view of the valve.

This internal combustion engine governor comprises generally a casing adapted to be 30 connected in the intake pipe of the engine between the carburetor and the engine cylinders or the intake yoke, and a normally open suction controlled valve movable in the casing in a direction contrary to the 35 flow of the gases through the casing whereby the valve when it approaches or nearly reaches its closed position, is relieved of the suction created by the vacuum in the engine cylinders.

10 1 designates the cylinders, and 2 the yoke of the intake pipe, which yoke is connected to the cylinders in the usual manner; 3 is the carburetor connected to the intake pipe section 4. The engine may be of any type 45 and include any number of cylinders. The intake yoke carburetor may also be of any desirable form, size and construction. 5 5 is the casing of the governor, the casing having inlet and outlet passages 6 and 7 60 which, when the casing is connected in the intake pipe, communicate respectively with the carburetor and the engine cylinders or intake yoke 2. In the illustrated embodiment of my invention the passages 6 and 7 5 are arranged at an angle to each other and the outlet passage 7 includes a circumfer-

ential groove or channel 8 extending around and opening into the passage 6, and a valve 9 is arranged to move crosswise of the outlet 7 in a direction contrary to the flow of the gas, (as indicated by the arrows) and into the inlet 6. Hence, the valve 9 when in its closed position is relieved of the suction created by the vacuum in the engine cylinder and is free to move toward its open position. Owing to the groove 8 the action of the suction on the valve is equal on all sides of the valve so that there is no tendency to bind on the part of the valve.

As here shown, the valve 9 reciprocates in a passage 10 aligned with the passage section 6 and located on the opposite side of the passage 7 to that on which the passage 6 is located, the passages 6 and 10 opening through opposite sides of the casing. The outer end of the passage 10 is closed by a cap 11. The valve is moved by the suction against the influence of a spring 12 located in the passage 10 and bearing against opposing shoulders 13 and 14 provided respectively on the casing and on the valve 9.

The passage 6 and valve 9 are shaped to effect a gradual shutting off of the gas by the suction as the valve 9 approaches or enters the passage 6, and as the valve approaches its closed position the peripheral surface of its advance end is opposed to and is of less diameter than the opposing surface of the inlet passage; and one of said opposing surfaces is formed tapered. As here illustrated, the advance end of the valve 9 is tapered as at 9^a. The tapering of the valve at 9^a provides the governor with a passage connecting opposite sides of the valve, whereby the communication between the inlet and exhaust passages is maintained to some extent when the valve is closed. The casing is provided with flanges 15 and 16 adapted to abut against complementary faces on the yoke 2 and intake pipe section 4 and the casing is held in position by cap screws 17 passing through suitable openings in said surfaces.

In operation, as the engine develops speed above normal, the valve 9 is drawn by the increased suction across the passage toward the inlet 6 and across the outlet 7, and owing to the tapered end of the valve 9, said valve will gradually cut off the outlet passage 7 and hence will be gradually relieved of the suction, whereupon the valve spring will again move the valve toward its open posi-

tion, so that in use the valve is constantly fluctuating toward and from its closed position, and, owing to the fact that the valve is relieved of the suction, and to the fact 5 that the passage 7 extends circumferentially around the inlet passage 6, said valve is very sensitive and efficient in its operation.

The governor of this application is of the same type as that shown in my pending 10 application Sr. No. 723,502 filed Oct. 2, 1912. One of the chief differences between the governors is that in the governor of this application the movement of the valve is in a direction contrary to the flow of gas instead of in the direction of the flow of gas 15 as in the copending application.

What I claim is:

1. An internal combustion engine governor comprising a casing adapted to be 20 connected in the intake pipe of the engine and having inlet and outlet passages, and a normally open suction controlled valve arranged to move toward the inlet passage into position to cut off the outlet passage, 25 which is connected to the engine cylinders, said valve being movable in a direction contrary to the flow of the gas through the passages whereby the valve is relieved of the suction when in its closed position, the 30 advance end of the valve being designed to enter the inlet passage and being of smaller diameter than the contiguous portion of the inlet passage and loosely fitting the same, substantially as and for the purpose set 35 forth.
2. An internal combustion engine governor comprising a casing adapted to be connected in the intake pipe of the engine and having inlet and outlet passages, and 40 a normally open suction controlled valve arranged to move toward the inlet passage which is connected to the engine carbureter, said valve being movable in a direction contrary to the flow of gases through the 45 passages whereby the valve is relieved of the suction when in its closed position, the advance end of the valve being designed to enter the inlet passage and the peripheral surface of such advance end being opposed 50 to the inner circumferential surface of the contiguous portion of the inlet passage and one of said opposing surfaces being tapered whereby a gradual shutting off of the gases and suction is effected, substantially as and 55 for the purpose described.

3. An internal combustion engine governor comprising a casing adapted to be connected in the intake pipe of the engine

and having inlet and outlet passages, and a normally open suction controlled valve arranged to move toward the inlet passage into position to cut off the outlet passage, which is in communication with the engine 60 cylinders, said valve being movable in a direction contrary to the flow of the gases through the passages whereby the valve is relieved of the suction when in its closed position, the advance end of the valve being 65 tapered slightly and designed to enter the inlet passage, substantially as and for the purpose specified.

4. An internal combustion engine governor comprising a casing adapted to be 70 connected in the intake pipe of the engine and having inlet and outlet passages arranged at an angle to each other, the former being in communication with the carbureter, and the latter with the engine cylinders, the casing being also formed with a valve passage aligned with the inlet passage and located on the opposite side of the outlet passage to that on which the inlet passage is located, and a valve movable in the 75 valve passage across the outlet into the inlet whereby the valve is relieved of the influence of the suction when in its closed position, the advance end of the valve being of slightly less diameter than the portion 80 of the inlet passage in which said advance end enters, substantially as and for the purpose specified.

5. An internal combustion engine governor comprising a casing for connection 90 in an intake pipe of the engine, the casing having inlet and outlet passages, and a normally open suction controlled valve arranged to move toward the inlet passage 95 which is connected to the engine cylinder, the valve being movable in a direction contrary to the flow of gas through the passages whereby the valve is relieved of the suction when in its closed position, and the 100 governor being formed with a passage for maintaining communication between the inlet and outlet passages as the valve approaches its closed position.

In testimony whereof, I have hereunto 105 signed my name in the presence of two attesting witnesses, at Syracuse, N. Y., in the county of Onondaga, in the State of New York, this 8th day of May, 1913.

AURIN M. CHASE.
